UNITED STATES PATENT OFFICE.

GEORGE W. CAMPBELL, OF NEW YORK, N. Y., ASSIGNOR TO VICTOR TYPEWRITER COMPANY, OF NEW YORK, N. Y., A CORPORATION OF NEW YORK.

TYPE-WRITING MACHINE.

1,114,227.

Specification of Letters Patent.

Patented Oct. 20, 1914.

Application filed January 6, 1909. Serial No. 470,895.

To all whom it may concern:

Be it known that I, GEORGE W. CAMPBELL, a citizen of the United States, and a resident of the city of New York, county 5 of New York, and State of New York, have invented certain new and useful Improvements in Type-Writing Machines, of which the following is a specification.

My invention relates particularly to a ribbon mechanism for typewriting machines in which the ribbon is automatically moved during the printing operation from a normal position into the path of an approaching type and returned to the normal position, thus leaving the printing point and the written matter unobscured by the ribbon or the parts which support and actuate it.

The objects of my invention are to provide in a ribbon mechanism of the character 20 set forth simple and efficient means for conveniently and easily regulating the mechanism so that different color fields of a multi-colored ribbon may be brought into service at will; to use selected portions of these 25 color fields; to use selected portions of an ordinary ribbon and to remove the ribbon entirely out of the printing field and render its actuating mechanism inoperative so that the machine may be readily employed for 30 cutting stencil sheets.

My invention consists of the features of novel construction, arrangement of parts and combination of devices having for their objects the above and other ends as described and illustrated in the accompanying drawings and specification and set forth in the claims.

In the drawing, wherein similar reference characters indicate corresponding parts in the several views, Figure 1 is a side view of so much of a typewriting machine embodying my invention as is necessary to the illustration of the latter; Fig. 2 is a plan view of the same machine with part of its top plate broken away to further show the arrangement of my device; Fig. 3 is a front view of the machine; Fig. 4 is a partial side view of the machine and a diagrammatic side view of the parts of my device 45 comprising generally a section of the machine taken on dotted line A, A, Fig. 2; Fig. 5 is a plan view of the device showing also those parts of the machine which serve as a support therefor; Fig. 6 shows the ribbon carrier which forms a part of my de-

vice; Fig. 7 shows the spring supporting plate for another part of my device.

I have shown my invention as it would be applied to a Victor typewriter in which machine it may readily be adopted without 60 altering its structural features. It will be understood, however, that my invention is readily applicable to other styles of machines.

Certain of the features herein set forth 65 are shown and broadly claimed in my application, Serial No. 343,725, filed November 16th, 1906. The present case relates to features not contained or claimed in said application.

The frame of the typewriter referred to and shown in the drawings comprises a base 1, corner posts 2 and a top plate 3. Key levers 4 are fulcrumed on a rod 5 running from side to side of the base plate 1 and are provided with finger keys 6. Type 70 bars 7 are segmentally arranged and fulcrumed on a segment (not shown) which forms a part of top plate 3 and are operated to strike upwardly and rearwardly against the front face of the platen 9 preferably 75 slightly above the horizontal axial plane thereof. This platen is carried by the carriage 10 which moves from side to side of the machine above the top plate 3. The letter space or step by step movements of 80 this carriage are controlled by a letter spacing mechanism (not shown in full) of which the vibrating dog carrier 11 forms a part. This dog carrier 11 is fulcrumed at 12 in the supporting bracket 13 depending 85 from the top plate 3. The dog carrier is actuated at each movement of the key levers 4 and the space bar 14, advancing the carriage a letter space at each key stroke. The movement of the dog carrier by the several 90 key levers 4 is accomplished by means of the universal bar 15 which extends from side to side of the machine below the key levers 4 so that it is depressed by the action of any 95 of the levers. This motion is communicated to the dog carrier by the connecting wires 16 which depend from the arms 17 of a universal bar rock shaft 18 pivotally mounted 100 on the base plate 1. This rock shaft carries a vertically disposed arm 19 from which the pull rod 20 extends rearwardly to the lower end of the lever 21 forming a part of the dog carrier 11. This lever 21 is normally held in contact with the stop 22 by the 105 spring 23. It will be seen, therefore, that 110

when any key lever is depressed the pull rod 20 and the lower end of the lever 21 are drawn forward by the action of the universal bar 14, the rock shaft 18 and the lever 5 arms 17 and 19.

In Fig. 3, I show the general arrangement of the ribbon with relation to the machine and the novel features which comprise my invention. The ribbon 24 is shown with a 10 dotted median line 25 which represents the demarcation between the two color fields 26 and 27. These color fields may not vary necessarily in color; one may be inked with a copying ink and the other with a non- 15 copying or record ink; also, it is understood that the ribbon may be uniformly inked throughout. The ribbon is coiled upon the ribbon spools 28 and is wound and unwound from one to the other longitudinally 20 in either direction across the machine in such manner that it will not obstruct the writing. To accomplish this end it is led from the right hand spool to the slotted guide arm 29,—see Figs. 1, 2 and 3. The 25 guide portion of this arm is arranged at an elevation and in an inclined plane parallel with and just below the line of sight of a written line on the platen 9. From the guide arm 29 the ribbon passes in a substantially 30 horizontal line to the upper guide member 30 of the vibrating or oscillating and longitudinally movable ribbon carrier 31. The term "vibrating or oscillating" is used with reference to the motion of this member normal 35 to the platen axis and the term "longitudinal" with reference to its movement parallel to such axis. This guide member 30 is shown in detail in Figs. 5 and 6. It is preferably formed of wire attached to the 40 upper right hand corner of the body of the ribbon carrier 31 from which it extends to the left parallel with the platen, thence forwardly and at an angle of forty-five degrees 45 in a right hand direction and in a plane parallel with the guide portion of the arm 29; thence rearwardly in a slightly higher level and in the same plane. As shown in 50 Fig. 2 the ribbon passes under this rearwardly projecting part which acts as a keeper, over and rearwardly under the inclined portion in a bias fold, thence over the horizontal portion and passes down parallel with the ribbon support to the lower guide member 32. This guide member 32 is shown 55 in detail in Figs. 4 and 6. It also consists of a suitable wire attached to the ribbon support and extending parallel therewith in an upwardly inclined right hand direction. Its upper end is bent back upon itself to act 60 as a keeper as in the guide member 30. The ribbon passes from guide member 30 as described in the manner shown in Fig. 3 to this lower guide member which it crosses in a bias fold and thence to the slotted guide 65 arm 33, see Fig. 2, from which it passes to

the left hand ribbon spool. The ribbon spools 28 are suitably supported on brackets 34 which depend from the top plate 3 as shown in Fig. 1. They rotate on shafts journaled in these brackets which shafts are 70 driven by the miter gears 36 which in turn are driven by the corresponding miter gears 37 which are supported and driven by the main ribbon driving shaft 38 which is journaled and supported in the brackets 39 75 which depend from the top plate 3, see Fig. 1. The main ribbon spool driving shaft is revolved to the right at each letter space movement of the carriage 10 by means well-known in the art through the medium of a 80 main-spring drum and its associated letter spacing mechanism which parts are not here shown. The main driving shaft 38 has a limited longitudinal movement by which means the driving gears 36 may be alternately engaged and the direction of travel 85 for the ribbon 24 may be changed at will so that it may be successively wound from one spool to the other. It will be understood that the general arrangement of the ribbon spool support and driving means as shown in Fig. 1 is duplicated on the opposite side of the machine.

I have thus far shown how the ribbon is supported during its longitudinal movements from spool to spool during the operation of writing. By the arrangement of the ribbon on and between the guide members 30 and 32, I secure a vertically disposed section of the ribbon supported by the ribbon carrier 31 which is wholly within the control of said carrier, the office of which is to interpose this section as an operative field between the types and the paper at each printing operation in a manner hereinafter described. This vertically disposed section or portion of the ribbon, it will be observed, lies crosswise of the axis of the platen or in the same direction as the direction of the platen shift movement. The platen shift movement in the Victor machine, to which my invention is shown applied in the drawings, is, like most machines at present in public favor, in a vertical direction. This direction of the platen shift is necessitated 100 from the style of machines referred to which is well known as front strike, visible typewriters. In such machines the ribbon employed is of narrow width, as distinguished 105 from the ribbon on the old style understrike machine, so as not to obscure the printing point or printing line. In front strike machines it is necessary to provide means for causing the ribbon to shift with the platen 110 when an upper case character is to be printed. This adds complication to the ribbon mechanism to provide this additional movement of the ribbon, which additional mechanism or increased complication is 115 avoided by my present invention by sup- 120

porting the operative or printing portion of the ribbon in a vertical or crosswise direction of the platen—that is a direction which is the same as, or parallel, to the direction of the platen shift. It will be seen that no additional shifting movement of the ribbon with the platen is necessary as by supporting the ribbon in this way it will cover the printing point in both upper and lower case positions of the platen, while at the same time the ribbon is retired out of the operator's line of sight in its normal position. In Fig. 3 the ribbon carrier 31 is shown as being centrally located in the machine and having its normal operative position opposite the writing point on the platen. The ribbon is therein shown threaded through its supporting members so as to expose a section of the ribbon crosswise of the line of writing. The different color fields are thus shown as occupying different vertical sections of the ribbon their division being represented by the dotted line 25. The ribbon carrier 31 is shown in a detailed plan view in Fig. 6 and in side elevation in Fig. 4. It is preferably made of sheet metal for lightness and strength. It is forked at its upper end, the inner edges of its tines forming edge guides for the ribbon in its passage from the upper to the lower guide member. The upper end of the right tine is lengthened and forms a support for the upper guide member. It is bent at α to form an obtuse angle in section as shown in Fig. 4. Projecting rearwardly from its lower end are arms 40 by means of which pivotal support is effected. Its lower end comprises a rectangular frame, the cross bar 41 of which is impinged by and forms an operating contact for the part which actuates it. Projecting from the front and just below the bend α is a bracket 42 forming a point of attachment for the retracting spring 43. The normal position of the ribbon carrier is illustrated in Fig. 4 where it is shown with its ribbon supporting portion inclined forwardly and fully below the line of vision, which is substantially at an angle of about 45 degrees to the horizontal. It has pivotal support in the yoke 45 being mounted therein by the arms 40 on the pivot screws 44. It is preferably maintained in its proper position by the stop plate 46^a which projects forwardly from a point on the top plate 3, Fig. 4, being held against this stop by the retracting spring 43 which extends from the arm 42 on the carrier to an arm 46 extending from the yoke 45. In Fig. 4, the pull rod 20 is shown as carrying an upwardly extending arm 47. At each printing operation of the machine this pull rod, acting as a movable member of the universal bar-operated letter spacing mechanism is drawn forward, carrying the arm 47 with it. Its upper end is arranged to occupy a position

of normal contact with the lower end of the ribbon carrier 31, especially on the cross-bar portion 41, Fig. 6. Forward movement of this arm as a part of the pull rod 20 causes the ribbon carrier 31 to oscillate on its pivotal support and carry the ribbon toward the platen and to properly interpose the vertical operative field between the types and the platen.⁹

The description thus far has related to the longitudinal travel of the ribbon, its supports by means of which it is caused to cover and uncover the writing point at each writing operation and the arrangement of the ribbon on the vibrating ribbon carrier which creates an operative field of that section of the ribbon which is led at this point longitudinally in a direction crosswise of the platen. To selectively employ different color fields of this operative section, or different portions of the respective color fields, I provide means for moving the ribbon carrier and its guide members in a direction parallel with the platen 9 to indexed predetermined positions in relation to the impression point of the types 8 on the platen 9. The yoke 45 in which the ribbon carrier 31 is pivotally mounted is rigidly attached to the rod 48, Fig. 5. This rod has its main support in the arms 51 shown on either side of the ribbon carrier. These arms are supported at the rear by the cross-bar 50 which in turn is secured to a lug 49 forming a part of the top plate 3, see Fig. 4, and at their forward ends by the screen plate 52, also having its support on a part of the top plate 3 which has been cut away for the purpose of making this illustration. The ribbon carrier 31 projects through a slot 52^a in said screen plate, as shown in Fig. 3. The rod 48 supports the yoke 45 intermediate of the arms 51 and passes through and extends beyond them on either side. The longer or right hand projection is extended and forms two right angled bends terminating in the parallel portion 48^a which passes through and is supported by a part of the top plate 3. This off-set portion 48^a in its support in the top plate 3 serves to secure the rod 48 against revolution, while permitting its axial movement. Means for giving this rod 48 indexed axial movement may be seen by an inspection of Figs. 1, 2 and 3, in which the operating rock shaft 53 is shown in detail supported at its forward end in the corner post 2 and at its rear end by the bracket 54 which depends from the right ribbon spool shaft support 34. This rock shaft 53 has lever arm 55 which comprises an attaching hub 55^a, extension 55^b and the slot or jaw 55^c. The lever arm engages at its slotted end the transverse portion of the rod 48, 48^b. The rock shaft 53 is carried through the corner post 2 and is bent at a point near the post to extend upward as an operat-¹³⁰

ing lever 56 which terminates in the ring or finger grip 57. In Fig. 2, in which a portion of the front right hand corner of the top plate 3 is broken away, is shown a plan view of means for indexing this operating lever 56 in its various angular positions. Fig. 3 shows the same in front elevation and Fig. 4 in right elevation. Mounted on the post 2 is supporting plate 58 shown in plan in Fig. 7. It is attached thereto by the hollow bolt 59 and nut 60. This hollow bolt serves as a bearing for the rock shaft 53. The screw 61 keeps the plate in a vertical position on the bolt. The upper end of the plate which is made from spring sheet metal is flexed forwardly away from the post 2. This plate has the forwardly projecting perforated ears 62. Revolubly mounted across the front of the plate and between these ears is the indexing arbor 63. This arbor is hexagonal in section and has on alternate facets the transverse notches 64 which are located in various positions longitudinally of the arbor and are alined in their various positions parallel to the radii of the operating lever 56 in its various angularly indexed positions. The arbor is revolubly adjusted by the thumb wheel 65 which is paned to correspond with the arbor and bears on its panes indicating characters 66. The arbor is held in its various adjusted positions by the spring pressure of its supporting plate 58 directed toward the operating lever 56 which is comparatively rigid and is held against the pressure of this spring member by the hub 55^a of the lever arm 55 which operates as a stop collar against the bracket 54, see Fig. 1, to oppose endwise movement of the rock shaft 53 in the direction of the lever 56. The sector portion of the plate 58, 67 is divided into indicating color fields; thus, the portion 68 may be black and the remaining portion 69 red.

45 The operation of my device is as follows: If a two color ribbon be used, it is wound upon the spools as usual, carried across the machine from side to side and threaded through the supporting members on the centrally disposed vibrating carrier, in such manner that its color divisions in the vertical operative field are reversed in their order from right to left to the color index for the operating lever. The notches on one face of the indexing arbor are arranged to lie wholly opposite one color on the index plate, those on another face opposite the remaining color field while the notches of another face embrace both fields and also a notch which indicates a blank. The operator selects the color field desired by revolving the arbor by means of the thumb wheel to expose the proper indicating character on that wheel. This brings those notches into play which are opposite the proper color

field on the index. The operator then brings the operating lever into engagement with a notch in that field. The operating arm transmits movement parallel to the platen to the ribbon carrier through its 70 rock shaft, the lever arm 55 and the supporting rod 48 upon which it is pivotally mounted. The proportions of the notch intervals, and the relative effective leverage of the operating lever and the connecting 75 lever arm are arranged to move the ribbon carrier sidewise, longitudinally of the platen and transverse of the vertical operative ribbon field a distance approximately that of a type face so that each change of the operating arm interposes a fresh longitudinal portion of the ribbon for use. If an ordinary ribbon of one color is used then the indexing arbor is turned to bring a face bearing notches covering the entire widthwise dimension of the ribbon. By bringing the operating arm into engagement with these various notches the entire width of the ribbon may be used in successive longitudinal fields. During the operations thus 80 described the operating portion of the ribbon carrier 41 has remained in operative contact with the driving arm 36. When it is desired to prepare stencils for mimeograph work or to cause the types to strike 85 directly against the stencil sheet or paper without the ribbon being interposed between them, the operating arm is engaged in a notch to the right on the indexing arbor indicated as blank. This moves the ribbon carrier in a corresponding direction to such an extent that it is entirely to the right of the writing point and the operating portion 41 is out of contact with the driving arm 47 and is not therefore vibrated during 90 the operation of the machine. During this time, the ribbon carrier is held by the stop 46 in position for reengagement with the driving arm 47, when the operating arm is 95 again shifted.

110 While I have described the mechanism as operating in a certain order or sequence it is to be understood that the several parts of the device may be differently arranged or manipulated in any desired order without departing from my invention. The construction herein set forth is preferential only as applied to a particular machine and is susceptible of change in detail for application to any machine without departing 115 from the invention in which—

I claim—

1. In a typewriting machine, the combination with the ribbon spools at the sides of the machine, of an oscillatory ribbon carrier for the ribbon at the printing point, angularly disposed guide members on said carrier for guiding the ribbon crosswise of the platen, a member on which said oscillatory carrier is mounted, said member ad- 120

justable in a direction parallel to the platen axis, and indexing means coöperating with said member and carrier for determining said adjustment of the member and carrier.

5 2. In a typewriting machine, the combination with ribbon spools and means for feeding the ribbon from spool to spool, of an oscillatory ribbon carrier for the operative field of the ribbon, ribbon deflecting 70 guide members on said carriers leading the operative field of the ribbon transversely of the printing line and normally exposing said line, hand operated means for setting said carrier in different positions with respect to the printing point in a direction parallel with the printing line and means for oscillating said carrier at printing operations.

3. In a typewriting machine, the combination with ribbon spools mounted on stationary axes, said spools arranged to deliver the ribbon from one to the other in a direction generally longitudinal with the printing line, of an intermediate ribbon support 80 adjacent the printing point, ribbon-deflecting guides arranged on said support to deflect the ribbon across the printing point in a direction transverse to and normally exposing said printing line, means for feeding the ribbon from spool to spool, manually operated means for adjustably shifting said ribbon support in the direction of the printing line and independently of the feed of the ribbon from spool to spool, indexing 85 means for limiting said adjustment of the ribbon support and means to oscillate said ribbon support at printing operation to cover and uncover the printing point.

4. In a typewriting machine, the combination of an oscillatory ribbon carrier adjacent the printing point, guides on said carrier arranged to lead the ribbon across the printing point in the vertical direction of the type impressions, hand-operated means 90 for adjusting said carrier to shift the ribbon widthwise of the printing point, selective indexing means for controlling said widthwise movement of the ribbon in accordance with selected widthwise portions of the ribbon and means for limiting the widthwise adjustment of the ribbon to the selected widthwise portions of the ribbon and means for oscillating said carrier to interpose the selected portion of the ribbon at 95 printing operation between the type and the printing point.

5. In a typewriting machine, the combination of universal-bar mechanism having an arm, an oscillating ribbon support for 100 a vertically disposed intermediate operative section of the ribbon comprising a carrier portion and an operating member in the path of the arm of the universal-bar mechanism, and hand operated means on which 105 the support is pivotally mounted for mov-

ing said operating member lengthwise of the platen independently of said arm.

6. In a typewriting machine, the combination of an oscillating ribbon support for a vertically disposed intermediate operative portion of the ribbon, said support comprising a carrier portion, guide members and an operating bar, an arm having operative contact with said bar, said arm actuated by the universal bar mechanism, and hand operated means for removing said operating bar out of operative contact with said arm to render the same inoperative. 75

7. In a typewriting machine, the combination of an oscillating ribbon support for a vertically disposed intermediate operative section of the ribbon comprising a carrier portion, guide members and an operating bar and a stop for holding said operating bar in line of operative contact with a universal-bar actuated arm. 80

8. In a typewriting machine, in combination with an oscillating ribbon support for a vertically disposed intermediate operative section of the ribbon comprising a carrier portion and guide members, an operating bar, a universal-bar actuated arm and a retracting spring for holding said operating bar in its normal position against a stop in operative line of contact with the universal-bar actuated arm. 90

9. In a typewriting machine, means for controlling the printing portion of the ribbon in its relation to the printing point, said means comprising selective indexing 100 means corresponding to different widthwise portions of the ribbon, said indexing means comprising a rotatable indexed arbor, detents on said arbor, and an operating arm having spring engagement with the arbor whereby said detents maintain said arm in 105 selected positions.

10. In a typewriting machine, the combination of a ribbon support, means for adjusting it lengthwise of the platen an operating arm for said means and a rotatable index arbor comprising a plurality of faces bearing detents in yielding operative relation to said operating arm. 110

11. In a typewriting machine, means for controlling the printing portion of the ribbon in its relation to the printing point to present different widthwise portions of the ribbon to the types, said means comprising an operating arm, a ribbon carrier movable by said arm in its relation to the printing point, an index arbor, a yielding support on which said arbor is mounted, said yielding support maintaining said arbor in contact with said arm to hold the arbor against 115 rotation. 120

12. In a typewriting machine, means for adjusting the printing portion of the ribbon to present different widthwise portions thereof to the types, said means comprising 125 130

- 6
- an oscillating ribbon carrier shiftable lengthwise of the platen, an operating arm for adjusting said carrier in said lengthwise direction, a rotatable index arbor for determining the said adjustments of the ribbon, a yielding support on which said arbor is mounted, said support holding the arbor in operative relation to said arm and hand operated means for rotating the arbor.
- 10 13. In a typewriting machine, means for adjusting the printing portion of the ribbon to present different widthwise portions thereof to the types, said means comprising an oscillating ribbon carrier shiftable lengthwise of the platen, an operating arm for shifting said carrier in the direction specified, a rotatable index arbor having yielding contact with said operating arm and controlling the position thereof, hand operated means for rotating said arbor, said hand operated means having indicating devices for the purposes described.
14. In a typewriting machine, the combination of a yieldingly mounted rotatable indexing arbor comprising a plurality of indexing faces bearing detents arranged in selective groups corresponding with coöperating fields of differing color characteristics of a ribbon and an arm engaged by said detents and adjustably controlling said arbor.
15. In a typewriting machine, the combination of an oscillating operating arm for controlling the widthwise position of a ribbon and an indexing arbor comprising a plurality of indexing faces bearing detents transversely of said faces in lines parallel with the said oscillating operating arm in its varicus angular relations to said arbor.
16. In a typewriting machine, means for adjusting the printing portion of the ribbon to present different widthwise portions thereof to the types, said means comprising a ribbon carrier for supporting the printing portion of the ribbon, means to shift said carrier to present different widthwise portions to the types, means to oscillate said carrier at printing operations, an indexing arbor having a plurality of indexing faces, detents for the said shifting means on said faces, one of said faces bearing detents corresponding to adjustments of the ribbon throughout its width and a detent corresponding to a position of the ribbon carrier which is inoperative with respect to the oscillating means.
17. In a typewriting machine a spring support for an indexing arbor comprising supporting arms and a sector portion said sector portion displaying indicating fields of differing color characteristics corresponding with like fields in a ribbon selectively adjusted thereby.
18. In a typewriting machine, an oscillating ribbon carrier for supporting the printing portion of the ribbon intermediate the

- ribbon spools, a guide member on said carrier and a coöperating stationary guide between said carrier and the ribbon spools, said guide member and guide being substantially parallel one with the other, and substantially parallel with the plane of vision of the operator, whereby the portion of the ribbon supported between said guide and guide member is presented edgewise to the sight.
19. In a typewriting machine, an oscillating carrier for the ribbon for supporting the printing portion thereof intermediate the ribbon spools, upper and lower angularly disposed guides on said carrier for leading the ribbon in opposite directions from said carrier respectively to the ribbon spools, said carrier and guides normally exposing the printing line, and said upper guide having a portion inclined away from the platen in a direction substantially parallel with the plane of sight.
20. In a typewriting machine, the combination with ribbon spools at the sides of the machine, of an oscillatory ribbon carrier at the printing point normally exposing said point, angularly disposed guide members on said carrier for guiding and maintaining an operative field of the ribbon substantially at right angles to the platen, automatically operated means for oscillating said carrier at printing operations to cover and uncover the printing point, a member on which said oscillatory carrier is mounted to maintain its right angular position with respect to the platen, hand operated means for adjusting said member and carrier lengthwise of the platen, to vary the position of the ribbon widthwise with relation to the printing characters, and indexing means for determining said adjustment.
21. In a typewriting machine, the combination of an operating arm oscillating on a main frame support and, in detent engagement therewith, an indexing arbor revolvably mounted on a yielding support, a shaft operated by said arm carrying a lever arm slotted for operative engagement with a rod mounted to move longitudinally, a yoke mounted on said rod pivotal bearings on the arms of said yoke, an oscillating support for the ribbon mounted to swing on said pivotal bearings, arms on said oscillating support and said yoke carrying a retracting spring for said support, a stop for limiting the action of said spring and maintaining said support in normal position, with an operating bar portion in line of contact with an actuating arm mounted on a movable part of a universal-bar actuated mechanism comprising a universal-bar extending beneath a series of type-bar actuating key-levers a rock shaft carrying lever arms supporting said universal-bar, a lever arm operatively connected by a horizontal pull rod to the

- oscillating operating arm of a vibrating letter space-dog carrier said bar being depressed at each printing operation and actuating said letter space dog carrier.
- 5 22. In a typewriting machine, the combination of an oscillating ribbon support longitudinally movable lengthwise of the platen, independently of the ribbon spools comprising a carrier and guide members on
- 10 which an operative section of the ribbon is maintained in vertical crosswise relation to the platen, a yoke on which the support is mounted to swing toward and from the printing point, a spring for returning said
- 15 support to normal position with its upper guide member out of the line of vision, a stop determining the normal position of said support, and a longitudinally movable rod on which said yoke is supported an off-
- 20 set portion in said rod holding it against revolution an angular portion in engagement with a slotted lever arm mounted on a shaft and vibrated by a detent controlled hand operating arm for effecting longitudinal adjustable movements to said rod.
- 25 23. In a typewriting machine, the combination of a member operated by the universal bar, of a platen, a pivotally mounted ribbon guide for the operative field of the ribbon, the pivotal axis of said ribbon guide

arranged parallel to the platen axis, means for shifting said ribbon carrier and its pivotal supports in a direction parallel with the platen axis, a member connected to said ribbon guide for operatively engaging the 35 member of the universal bar throughout a portion of the shifting movement of the ribbon guide corresponding to the width of the ribbon.

24. In a typewriting machine, the combination of a member operated by the universal bar, a platen, a pivotally supported ribbon guide for the operative field of the ribbon, a member connected with said guide and arranged to be engaged by the member 40 of the universal bar for oscillating said guide on its pivots, means for adjustably moving said ribbon guide in the line of its pivotal axis to present different widthwise portions of the ribbon to the printing point, 45 said adjusting means having a range of movement sufficient to carry said members out of engagement when the ribbon is shifted widthwise clear of the printing point.

GEORGE W. CAMPBELL.
